UNITED STATES PATENT OFFICE

2,613,364

FLEXIBLE BRIDGE

Clifton Hurtt Deringer, Patton, Pa.

Application November 1, 1949, Serial No. 124,904

2 Claims. (Cl. 2-255)

1

The invention relates to a flexible form which can be quickly and easily applied to the selvage edges of a coat seam extending downwardly from the lower collar line of a coat, on the inside of the back of the coat, and constructed in a manner whereby the selvage edges on each side of the seam are gripped and held in position so that the flexible semi-stiff form will maintain its applied position at all times and prevent transverse buckling or creasing of the coat back, immediately below the collar, thereby obviating an unsightly appearance, now the difficulty experienced with many coats.

A further object is to form the coat retaining form from a flexible semi-rigid material; to provide the form with opposing gripping elements adapted to engage the inner and outer sides of the selvage edges for holding the form in applied position.

With the above and other objects in view the invention resides in the combination and arrangement of parts as hereinafter set forth, shown in the drawing, described and claimed, it being understood that changes in the embodiment of the invention may be made without departing from the scope of the claims.

In the drawing:

Figure 1 is a perspective view of the device, showing the device applied to the selvage edges on the inner side of the back seam on a conventional form of coat.

Figure 2 is a perspective view of the garment form.

Figure 3 is a view similar to Figure 2, but showing the gripping parts of the form flexed outwardly for application to the selvage edges.

Figure 4 is a horizontal sectional view taken on line 4-4 of Figure 1.

Figure 5 is a horizontal section taken on line 5-5 of Figure 2 showing the gripping elements flexed outwardly in dotted lines.

Figure 6 is a vertical transverse sectional view taken on line 6-6 of Figure 4, showing the form in side elevation.

Referring to the drawing, the numeral 1 designates the back of a conventional form of coat, and 2 the collar of the coat. Extending downwardly in the back is a conventional form of seam 3, which seam is provided with selvage edges 4, which extend in opposite directions, and the form hereinafter set forth is designed to be applied to the upper end of the seam 3, and

5 to grip the selvage edges 4 by gripping elements. The form 5 is preferably rectangularly shaped as shown and formed from a flexible material, but of sufficient thickness to maintain the smooth flat form of the back 1 of the coat. Celluloid or any other material may be used. The form 5 is preferably slightly concaved, as shown, to conform to the curvature of the back.

10 The upper and lower ends of the form 5 are provided with transverse slits 6, and with a vertical slot 7 connecting the slit 6, thereby forming selvage gripping flanges 8, which flanges are adapted to be flexed outwardly as shown in Figure 3 for gripping the inner faces of the selvage edges. Flanges 8, adjacent their upper and lower ends, are provided with U-shaped cuts extending entirely therethrough in reverse relation, and which U-shaped cuts form flexible tongues 10, which tongues are flexed outwardly when applying the device, and adapted to engage and grip the outer faces of the selvage edges 4 and in combination with the gripping flanges 8 positively grip the selvages from both sides, thereby maintaining the form in positive position without any other securing means and in a manner whereby the device may be easily and quickly applied or removed from the garment. The ends of the flanges 8 are preferably recessed as at 11 so that the selvage edges will not be bunched at these points, which is desirable at the free edges of the selvages.

15 In applying the device, the coat back is placed on a smooth surface and the flexible flanges 8 flexed inwardly for the reception of the selvage edges between the flanges 8 and the flexible tongues 10, care being taken to have the back smooth. After the tongues are released, the selvage edges will be gripped and the back of the coat, below the collar will be maintained smooth against any transverse creasing when the user moves his arms or changes his position.

20 From the above it will be seen that a crease preventing device is provided, for the back of a coat, which device is formed from a single piece of material, and one which may be cheaply manufactured and sold. It will be noted that the slot 7 is of sufficient width, as shown in Figure 4, to allow the seam 3 to assume a position between the adjacent edges of the flanges 8.

25 The invention having been set forth what is claimed as new and useful is:

30 1. A wrinkle preventer, said wrinkle preventer

comprising a rectangularly shaped flexible body, said body having an I-shaped slot therein thereby forming inwardly extending flanges within the lines of the body, struck-out flexible lugs struck-out from portions of the flanges adjacent their sides and extending in the same direction as the direction of each flange, said lugs adapted to grip seam flanges and clamp the seam flanges against the flanges of the wrinkle preventer.

2. A device as set forth in claim 1 wherein the wrinkle preventer flanges terminate spaced from each other.

CLIFTON HURTT DERINGER.
